MATERIAL GATHERING AND LOADING MACHINE

Frank Cartlidge, Chicago, Ill., assignor to Goodman Manufacturing Company, Chicago, Ill., a corporation of Illinois

Application May 20, 1938, Serial No. 208,969

9 Claims. (Cl. 198—7)

This invention relates to improvements in material gathering and loading machines particularly adapted for loading coal at the working face of a mine.

The principal object of the invention is to provide a simple and efficient machine of the character described of a low overall height suitable for operation in thin seams of coal, including a novel form and arrangement of conveyers and hopper construction between the elevating and discharge conveyers insuring a continuous flow of material between the conveyers when in various positions of adjustment with respect to each other and permitting utmost flexibility of movement of the conveyers and still retaining the dimensions of the machine to the low limits requisite for operation in thin seams of coal.

An application Serial No. 108,189, filed by me October 29, 1936, discloses a loading machine of a type somewhat similar to that shown by my present invention. My present invention, however, differs therefrom in the conveyer arrangement and closure means between the discharge and elevating conveyers.

Other objects of the invention will appear from time to time as the following description proceeds.

This invention may best be understood by referring to the accompanying drawings in which:

Figure 1 is a view in side elevation of a machine constructed in accordance with my invention;

Figure 2 is a plan view of the machine shown in Figure 1 showing parts in section and showing the extreme ends of the front and rear conveyers broken away;

Figure 3 is an enlarged view of the central portion of the machine in side elevation, with parts broken away and shown in substantially longitudinal section;

Figure 4 is an enlarged plan view of the central portion of the machine drawn to substantially the same scale as Figure 3, with parts broken away and shown in section;

Figure 5 is a fragmentary front end view of the machine drawn to the same scale as Figure 4, with the elevating conveyer broken away, showing certain parts in transverse section;

Figure 6 is a fragmentary transverse sectional view of the machine, drawn to substantially the same scale as Figure 5, and taken substantially along line 6—6 of Figure 4;

Figure 7 is a sectional view taken substantially

along line 7—7 of Figure 4 and drawn to a slightly larger scale than Figure 4;

Figure 8 is a detailed fragmentary view in side elevation showing certain details of the hopper arrangement between the discharge and receiving ends of the elevating and discharge conveyers; and

Figure 9 is a diagrammatic fragmentary plan view of the central portion of the machine showing the conveyers in a different position than in Figure 2, in order to show certain details of the hopper arrangement not shown in Figure 2.

Referring now to the details of the machine as shown in Figures 1 and 2, the main elements thereof consist of a wheeled truck or main frame 10, an inclined elevating conveyer 11 projecting from the front end of said main frame and having gathering mechanism 12 on the forward end thereof, and a discharge conveyer 13 extending from beneath the rear end of said elevating conveyer and thence rearwardly in extended overhanging position beyond the rear end of said main frame so as to discharge material into cars or the like.

The main operating parts of the machine are driven from a motor 15 supported at the rear end of the main frame 10 between side frame members 16, 16 thereof. Said motor has power connections for driving the truck wheels, for swinging the gathering and loading element in a horizontal plane, for raising or lowering said gathering and loading element relative to the ground, and for driving the gathering devices and associated conveyer.

The truck driving connections are provided through a main transmission gear case 18 disposed in front of the motor and are similar to those described in my prior Patent No. 2,027,091 which issued on Jan. 7, 1936. Said driving connections are no part of my present invention so will not herein be shown or described in detail.

The drive connections to the elevating conveyer 11 and gathering mechanism 12 include a shaft 19 which is driven from the motor 15 in a manner similar to that shown in my aforementioned prior patent. Said shaft extends from the main transmission gear case 18 and has a bevel pinion 20 mounted on its front end which meshes with and drives a bevel gear 21. Said bevel gear is journaled in the truck frame 10 for rotation about a vertical axis on a bearing 22 mounted on a vertical shaft 23. Said shaft is mounted in and extends upwardly from a boss 24 projecting upwardly from the truck frame. Said boss forms a bearing support for a swiveled

gear casing and support frame 25 for the front elevating conveyer. Said support frame rests on and has slideable bearing engagement with a forwardly projecting portion 28 of the frame for said truck. The bevel gear 21 meshes with and drives a bevel pinion 26 on the rear end of a longitudinal shaft 27. Said shaft is journaled in said gear casing and support frame and extends in a forward and angularly upward direction along said frame. A bevel pinion 29 is mounted on the other end of said shaft and meshes with and drives a bevel gear 30, secured to a transversely extending shaft 31, for driving said shaft. Said last mentioned shaft is journaled adjacent its ends in said gear casing and support frame and projects from the side of said casing which is its left hand side when looking towards the forward end of the machine. A sprocket 32 is mounted on the projecting end of said shaft and forms a means for driving the elevating conveyer 11 and gathering mechanism 12. Said last mentioned shaft besides forming a drive member for said elevating conveyer also has gearing connected thereto intermediate the ends thereof for swinging said conveyer from side to side about the pivotal axis of the frame 25 and elevating or lowering the forward end of said conveyer with respect to the ground in a manner which will hereinafter more clearly appear as this specification proceeds.

The elevating conveyer 11 includes an inclined vertically swingable elevating section 33 and a rearwardly projecting horizontal discharge section 35 which is fixed against vertical movement. Said inclined elevating section includes a pair of spaced apart side frame members 37, 37 having upwardly and outwardly flared sides. Said side frame members are connected together by a plate 39 extending therealong and forming a bottom for the conveyer. A pair of bearing bosses 55, 55 project laterally from the outer sides of the upper rear end of said side frame members. Said bosses form a pivoted bearing support for said inclined section and are pivotally mounted adjacent the upper forward end of the gear casing and support frame 25 on a pair of spaced apart bearing support members 34, 34, herein shown as being of a split construction.

The horizontal discharge section of said elevating conveyer is fixedly mounted on the upper side of said gear casing and support frame and extends rearwardly from said inclined section. Said discharge section is arranged in cascade relationship with respect to a receiving hopper like section 36 of the discharge conveyer 13, which is likewise fixed from vertical movement, and which is disposed closely adjacent the lower portion of said horizontal discharge section.

An apron 40 extends across the forward end 60 of the side frame members 37, 37 and upwardly along opposite sides thereof and forwardly therefrom to the ground, and forms a support for the gathering mechanism 12. Said gathering mechanism may be of a type similar to that shown 65 in my prior Patent No. 2,066,137 of Dec. 29, 1936, and includes a pair of spaced endless chains 42, 42 guided for orbital movement along opposite sides of said conveyer and having spaced apart gathering arms 43, 43 projecting laterally therefrom.

70 The discharge section 35 of the elevating conveyer 11 includes a pair of side frame members 44, 44 connected together by a horizontal plate 45 which forms a bottom for the conveyer. An idler shaft 46 is adjustably journaled in said side frame members adjacent the discharge end there-

of and, as herein shown, has a pair of idler rollers 47, 47 mounted thereon, about which the conveying element turns (see Figures 3 and 6).

The conveying element includes a pair of spaced apart endless chains 49, 49 having transversely disposed flights 50, 50 connected therebetween at intervals therealong. Said flights have beveled advance and retreating conveying surfaces, the advantage of which will hereinafter more clearly appear as this specification proceeds. Said chains extend upwardly along the plates 39 and 45 and around the idler rollers 47, 47. From said idler rollers said chains extend forwardly over guide rollers 51, 51 disposed beneath the plate 45, and under drive sprockets 53, 53 on a transversely extending shaft 54 journaled in the bearing bosses 55, 55 coaxial with the axis of vertical adjustment of said elevating conveyer. From said drive sprockets said endless chains extend downwardly along the under side of the plate 39 to and around suitable idler rollers at the forward end thereof, and thence upwardly along the upper side of said plate.

The transverse shaft 54 is driven from the sprocket 32 on the outer end of the shaft 31 by means of a chain and sprocket drive generally indicated by reference character 57, and a suitable friction clutch (not shown) disposed coaxial with said shaft. Said friction clutch is of an ordinary construction and is no portion of my present invention so will not herein be shown or described in detail.

The endless gathering chains 42, 42 are herein shown as being driven from the shaft 54 by means of a pair of universal drive shafts 59, 59 in a manner similar to that shown and described in a prior application Serial No. 172,895 filed by me on November 5, 1937. Said shafts extend along the outer sides of the conveyer and are driven from the shaft 54 by means of a pair of meshing spur gears indicated by reference character 60, which drive a transverse shaft 61. A pair of meshing bevel gears 62, 62 are disposed adjacent each end of said shaft and are driven therefrom and rotatably drive the shafts 59, 59. A bevel gear drive of an ordinary construction (not shown) may be provided from the forward ends of each of said universal drive shafts to said endless gathering chains for driving said chains.

A compression spring 64 is interposed between the forward end of the support frame 25 and the underside of the elevating conveyer 11, and encircles a cylindrical member or pipe 65 encircling and mounted for slideable movement with respect to a shaft 66. The lower end of said shaft has a flanged collar 67 secured thereto and abutting one end of said spring. Said shaft is provided with an integrally formed yoke 68 which is pivotally connected to a forward projection 69 of said support frame by means of a pivotal pin 70 (see Fig. 3). A flanged collar 71 is secured to the upper end of the pipe 65 and is abutted by the upper end of said spring. A yoke 72 projecting upwardly from said pipe is pivotally secured to a bracket member 73, projecting downwardly from the central portion of the frame for said elevating conveyer (see Figure 1).

The forward end of the inclined conveyer 11 is elevated or lowered with respect to the ground by means of a pair of spaced apart threaded shafts 74, 74 threaded within the hubs of worm gears 75, 75. Said worm gears are journaled on their hubs in housings 76, 76 projecting laterally from opposite sides of the gear casing and support frame 25, and are meshed with worms 77, 77 on

opposite ends of a transversely extending shaft 79. A member 80 slidably guided in a guide 81 formed in an upwardly projecting portion 82 of the housing 76 is secured to the upper end of the threaded shaft 74 (see Figures 3 and 5). A roller 83 is rotatably mounted in said member and engages an inclined surface 84 of a foot 85 depending from the side frame member 37 of the conveyor frame (see Fig. 3). Thus rectilinear movement of said shafts and rollers will pivot the inclined portion 33 of said elevating conveyor in a vertical plane.

The drive to the shaft 19 includes a bevel pinion 86 mounted on the lower end of a vertical shaft 87. Said bevel pinion is driven from the bevel gear 30. A bevel pinion 88 is mounted on the upper end of said vertical shaft and meshes with and drives opposing bevel gears 89, 90 freely mounted on a transversely extending sleeve 90 (see Figure 5). Said bevel gears are selectively connected with said sleeve by means of a pair of friction clutches 91, 91 herein shown as being of the friction disk type. A chain and sprocket drive generally indicated by reference character 93 is provided to operatively connect said sleeve with the shaft 19.

The drive for swinging said elevating conveyor from side to side includes a pair of oppositely disposed bevel gears 94, 94 mounted coaxial with the transverse shaft 31 and adapted to be operatively connected with said shaft by means of suitable friction clutches generally indicated by reference characters 95, 95 (see Figure 4). Said clutches are of an ordinary construction well known to those skilled in the art and are no portion of my present invention so will not herein be shown or described in detail. A bevel gear 96 mounted on a shaft 97 meshes with and is selectively driven from either of said first mentioned bevel gears. A worm 98 is mounted on the shaft 97 and meshes with and drives a worm gear 99 on a vertical shaft 100. A sprocket 101 is secured to the lower end of said shaft and meshes with a suitable drive chain 102. Said drive chain is yieldably secured at its ends to opposite sides of the truck frame 10 and extends around the forward end thereof so that rotation of said sprocket will cause swinging movement of said gathering and loading element.

With reference now in particular to the discharge conveyer 13, the receiving hopper like section 36 thereof, which is best shown in Figures 2, 3, 4, and 9, is disposed centrally of the axis of turning movement of said discharge and elevating conveyers and underlaps the discharge end of the elevating conveyer 11 in relatively close relationship with respect thereto, and the spacing between the chains of said conveyers is less than the radius of the loop subscribed by the outside of the chain 49 as it turns around the direction changing device 47. Said receiving hopper like section includes a pair of spaced apart side frame members 103, 103 secured at their lower ends to a turntable 104 (see Figure 6). Said turntable rests on a plate 105, forming a portion of the truck frame, and is guided on said plate for rotatable movement about an axis coaxial with the axis of pivotal movement of the gear casing and support frame 25, by an annular shouldered guide member 106 secured to said plate by means of cap screws. The shouldered portion of said guide member engages an annular shouldered recess formed in said turntable to prevent upward tilting movement of said turntable with respect to said plate.

A discharge section 107 of said discharge conveyor is pivotally connected to the hopper like section 36 of said discharge conveyor, on a horizontal transversely disposed shaft 109, which is mounted adjacent the rear end of the side frame members 103, 103 of said hopper like section (see Figure 4). Vertical adjustment of said discharge section of said receiving conveyor, to accommodate said conveyor to cars of varying heights is effected by means of a pair of spaced apart adjusting screws 110, 110 mounted on opposite sides of the side frame members 16, 16 of the truck 10 and secured at their upper ends to an arcuate shaped support member 111 which forms a slideable support for said discharge conveyor (see Figures 1 and 2). Said adjusting screws are rectilinearly moved by power to raise or lower said arcuate shaped support member and discharge conveyor in a manner similar to that described in my prior Patent No. 2,066,137, so the power drive thereto will not herein be shown or described in detail.

Swinging of said discharge conveyer from side to side is effected by means of a sprocket 112 meshing with a drive chain 108 which is yieldably secured at its ends to opposite sides of the support member 111 (see Figure 2). Said sprocket is driven from a motor 113, mounted on the side of said conveyer frame which is its left hand side when looking towards the front of the machine, by means of a suitable gear reduction train which is not herein shown or described since it is no part of my present invention.

The means for moving material along said hopper like section and discharge section includes a pair of spaced apart endless chains 114, 114 connected together by flights 115, 115 at suitable intervals. Said flights have beveled forward and retreating faces and are similar to the flights 50, 50. Said endless chains extend around direction changing devices 116, 116 on a transverse shaft 117 mounted at the forward end of said hopper like section between the side frame member 103, 103. From said direction changing devices said endless chains extend upwardly along a plate 118 mounted between said side frame members, and a plate 119 mounted between side frame members 120, 120 of the discharge section 107, to the rearward end of said discharge section. At this point said endless chains are trained around a suitable direction changing device at the rear end of said discharge section (not shown) and from thence extend forwardly along said discharge section beneath the plate 119. Said endless chains are driven from the motor 113 in a suitable manner, which is not herein shown or described since it is no part of my present invention.

A horizontal U-shaped plate 121 extends around the upper forward end of the hopper like receiving section 36 and rearwardly along the outer sides of the side frame members 103, 103 (see Figures 2, 3, and 9). The inner central portion of said plate overlaps the chains 114, 114 and flights 115, 115 at their forward turning point and underlaps the chains 49, 49 and flights 50, 50 and serves to check the tendency of said flights to carry material towards the forward end of the machine. In cases where the material such as coal, or coal and rock, has piled up in the hopper like section 36, which may be caused by stopping of the discharge conveyer while the elevating conveyer continues to operate, and the two conveyers are again put in operation, the inclined advance faces of the flights may ride over or under the lumps of rock or coal, as the 75

case may be, or deflect them from the respective flights. This will prevent fouling of the conveyers, and lump coal or rock which might be moved in a forward direction by the returning flights 58, 59 will be engaged with the edge of the plate 121 by said flights and be sheared by said flights and plate.

This construction and arrangement of conveyers, besides aiding in maintaining the vertical dimensions of the machine to those necessary for operation in thin seams of coal, also prevents the lower run of the elevating conveyer from carrying material towards the forward end of the machine and enables the discharge conveyer 10 to pick up loose material discharged from the elevating conveyer while it is still moving towards the discharge end of the machine. This reduces the tendency for material to pile up at the receiving end of the discharge conveyer and insures a continuous flow of material from one end of the machine to the other when both conveyers are in operation.

Referring now in particular to the novel form of adjustable side wall construction between said elevating and discharge conveyers, a means is provided to retain the material within the lateral boundaries of the discharge conveyer as closely as possible and to prevent undue widening of the stream of material at the discharge point of said elevating conveyer, so that the kinetic energy of the material will not be lost upon its transfer from one conveyer to the other and thus causing the flow of coal between the two conveyers to be continuous when the conveyers are in various positions of adjustment with respect to each other. Said means includes an extensible side wall connection between the rear end of the discharge section 35 and the hopper like section 36, which includes the horizontal plate 121 which forms a base along which the extensible side walls may slidably move (see Figures 2, 6, and 9). The details of said telescopic side walls are best shown in Figures 6, 7, 8, and 9, and said side walls include a pair of pivoted curved side walls 122, 122, which extend rearwardly along said plate from opposite sides of the discharge section 35 of the elevating conveyer 11. Pivot pins 124, 124 pivotally connect said side walls to laterally extending forked brackets 123, 123 projecting laterally from the side frame members 44, 44 of said discharge section, adjacent the rear end thereof. A compression spring 125 encircles each pin 124 and is interposed between an upper portion of said bracket 55 and a hinge portion of said side wall to permit yieldable movement of said side wall in an upward direction, and thus prevent binding in cases where coal might become wedged between the plate 121 and said side wall.

60 The side walls 122, 122 are provided with a relatively vertical lower wall portion and an outwardly and upwardly extending upper retaining portion forming in effect a flared hopper which includes the plate 121 and receiving section 36. A slot 126 extends longitudinally along the lower wall portion of each of said side walls and is adapted to be engaged by a guide member 127 secured to and extending outwardly from an extensible side wall 128 (see Figure 7). A retaining member 129 abuts the outer side of the guide member 127 and, as herein shown, is secured to the wall 128 by the same member which secures said guide thereto, and slidably engages the outer side of the side wall 122. The side wall 128 is 65 curved to conform to the formation of the side

wall 122 and also has a transverse cross section which corresponds to that of the side wall 122.

The side walls 128, 128 are each provided with a pin 130 at the free end thereof, the ends of which pins project above and below said side walls. The lower end of each of said pins is slidably guided in a grooved guide 131 formed in the plate 121 and the upper projecting end of each of said pins is guided in a guide groove 132 formed in the underside of a plate 133 secured to and projecting laterally from the side frame members 103, 103 (see Figures 7 and 8). Each of said guides is herein shown as being of a rectilinear formation and extends along the outer side of the discharge section 107 of said discharge conveyer in a forwardly diverging direction from the conveyer.

Closure members 134, 134 are pivotally connected to the outer sides of each side frame member 103 adjacent the forward end of the discharge section 107, to yieldably engage the side walls 122, 122 and 128, 128 and prevent material from clogging the grooved guides 131, 131. Each of said closure members is provided with a lower inwardly extending horizontal portion 135 which rests on the plate 121 and serves to extend over and close the guide 131 when the conveyers are in a position where said guide would normally be open, such as is shown by dotted lines in Figure 4. Each of said members is yieldably engaged 30 with the inner sides of said side walls by means of a tension spring 136 secured at one of its ends to the frame of said hopper like section of said discharge conveyer, and secured at its opposite end to a lever arm 137 which extends from the lower end of a shaft 138, upon which said closure member is secured.

It will be seen from the foregoing that the pivoted and extensible side walls 122, 122 and 128, 128 closely confine the coal within the limits of the discharge conveyer when the two conveyers are in various positions of adjustment with respect to each other, and that this arrangement of side walls together with the spacing between the conveyers at their discharge and receiving 40 ends, which reduces vertical clearance to the minimum necessary to permit the conveyers to freely travel with respect to each other when loaded, lessens the tendency of the material to lose momentum upon being transferred from one 50 conveyer to the other and pile up in the hopper section of the discharge conveyer when the two conveyers are running.

It will also be seen that the arrangement and construction of the elevating and discharge conveyers is such that the low overall dimensions of the machine are maintained when the conveyers are in various positions of adjustment with respect to each other in both horizontal and vertical planes by constructing the elevating conveyer in two sections, one of which is stationary in a vertical direction and forms a relatively short discharge section, and the other of which is vertically swingable with respect to said stationary section; and by providing a discharge conveyer 65 adjustable in a horizontal plane about the axis of pivotal adjustment of said elevating conveyer which includes a receiving section which underlaps said discharge section in relatively close relation with respect thereto, and which is mounted so as to be immovable in a vertical direction, and a discharge section pivotally connected to said receiving section for movement about a horizontal transverse axis disposed adjacent the rear end of said receiving section, thus 70 75

permitting a greater range of adjustment of said elevating and discharge conveyors without the sacrifice of height.

It will further be seen that the plate 121 disposed between the two conveyors, together with the beveled advance faces of the flights of said conveyors, prevents fouling of the conveyors with large lumps of material such as rock, or coal of a hard nature, and thus permits the discharge and receiving ends of the respective conveyors to be spaced with less vertical clearance than formerly.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a loading machine, a frame, an elevating conveyor extending forwardly of said frame and mounted on said frame for pivotal movement about a vertical axis, a discharge conveyor having a receiving end disposed beneath the discharge end of said elevating conveyor, and an extensible side wall connection between said conveyors to confine the material to the path of said discharge conveyor when said conveyors are disposed in various angular relationships with respects to each other including a relatively horizontal plate extending along the sides and across the forward end of said discharge conveyor, a pair of side walls adapted to slidably move along said plate, said side walls having pivotal connection with opposite sides of said elevating conveyor at points disposed adjacent the discharge end thereof, another pair of side walls adapted to slide on said plate, each of said latter side walls having slidable engagement with one of said first mentioned side walls at one of their ends, and having slidable guiding connection with said plate at their opposite ends.

2. In a loading machine, a frame, an elevating conveyor extending forwardly of said frame and mounted on said frame for pivotal movement about a vertical axis, a discharge conveyor mounted for pivotal movement about a vertical axis and having a receiving end disposed beneath the discharge end of said elevating conveyor, and an extensible side wall connection between said conveyors to confine the material to the path of said discharge conveyor when said conveyors are disposed in various angular relationships with respect to each other including a relatively horizontal plate extending along the sides and across the forward end of said discharge conveyor, a pair of concavely curved side walls having slidable engagement with the upper side of said plate, each of said side walls having pivotal connection with opposite sides of said elevating conveyor at points spaced laterally from the sides thereof, another pair of curved side walls, each of said latter side walls having slidable engagement with one of said first mentioned curved side walls at one of their ends so as to extensibly move with respect thereto and having slidable guiding connection with said plate at their opposite ends.

3. In a loading machine, a frame, an elevating conveyor extending forwardly of said frame and mounted on said frame for pivotal movement about a vertical axis, a discharge conveyor having

a receiving end disposed beneath the discharge end of said elevating conveyor, and an extensible side wall connection between said conveyors to confine the material to the path of said discharge conveyor when said conveyors are disposed in various angular relationships with respect to each other including a relatively horizontal plate extending along the sides and across the forward end of said discharge conveyor, a pair of concavely curved side walls having slidable engagement with the upper side of said plate, each of said side walls having pivotal connection with its respective side of said elevating conveyor at points spaced laterally from the sides thereof, another pair of curved side walls, each of said latter side walls having slidable engagement with one of said first mentioned curved side walls at one end so as to extensibly move with respect thereto, a pair of rectilinear guides formed in the upper side of said plate, each of said guides being spaced from a side of said discharge conveyor and extending therealong in a forwardly direction in diverging relationship with respect thereto, and guiding connections between said guides and the opposite ends of said last mentioned curved side walls.

4. In a loading machine, a frame, an elevating conveyor extending forwardly of said frame and mounted on said frame for pivotal movement about a vertical axis, a discharge conveyor having a receiving end disposed beneath the discharge end of said elevating conveyor, and an extensible side wall connection between said conveyors to confine the material to the path of said discharge conveyor when said conveyors are disposed in various angular relationships with respect to each other including a relatively horizontal plate extending along the sides and across the forward end of said discharge conveyor, a pair of concavely curved side walls having slidable engagement with the upper side of said plate, each of said side walls having pivotal connection with its respective side of said elevating conveyor at points spaced laterally from the sides thereof, another pair of curved side walls, each of said latter side walls having extensible connection with one of said first mentioned curved side walls, a pair of rectilinear guides formed in the upper side of said plate, each of said guides being spaced from a side of said discharge conveyor and extending therealong, guiding connections between said guides and said last mentioned curved side walls, and means to prevent the accumulation of material in said guides comprising a pair of closure members mounted on opposite sides of said discharge conveyor and having yieldable engagement with the inner sides of said side walls.

5. In a loading machine, a frame, an elevating conveyor pivotally mounted on said frame for movement about a vertical axis, a discharge conveyor having a receiving end disposed beneath the discharge end of said elevating conveyor, and an extensible side wall connection between said conveyors to confine the material to the path of said discharge conveyor when said conveyors are disposed in various angular relationships with respect to each other including a relatively horizontal plate extending along the sides and across the forward end of said discharge conveyor, a pair of concavely curved side walls having slidable engagement with the upper side of said plate, each of said side walls having pivotal connection with one side of said elevating conveyor, another pair of curved side walls, each of said

latter side walls having extensible connection with one of said first mentioned curved side walls, a pair of rectilinear guides in the upper side of said plate, each of said guides extending along an outer side of said discharge conveyer, guiding connections between said guides and said last mentioned curved side walls, and means to prevent the accumulation of material in said guides comprising a pair of closure members, said closure members being pivotally mounted at opposite sides of said discharge conveyer for yieldable engagement with the inner side of said side walls and having an inwardly extending portion resting on said plate and forming a cover for the open portion of said guide.

6. In a loading machine, a frame, an elevating conveyer mounted on said frame for pivotal movement about a vertical axis, a discharge conveyer having a receiving end disposed beneath the discharge end of said elevating conveyer, and an extensible side wall connection between said conveyers to confine the material to the path of said discharge conveyer when said conveyers are disposed in various angular relationships with respect to each other including a plate extending along the sides and across the forward end of said discharge conveyer, a pair of curved side walls having slidable engagement with the upper side of said plate, said side walls having pivotal connection with opposite sides of said elevating conveyer, another pair of curved side walls, said last mentioned side walls having extensible connection with said first mentioned curved side walls, a pair of rectilinear guides in the upper side of said plate, each of said guides extending along the outer side of said discharge conveyer, a pair of plates spaced above said first mentioned plates, said plates each having a guide aligned with said respective guide in said lower plate in the underside thereof, and means on said last mentioned curved side walls having slidable engagement with said upper and lower guides.

7. In a loading machine, a frame, an elevating conveyer mounted on said frame for pivotal movement about a vertical axis, a discharge conveyer having a receiving end disposed beneath the discharge end of said elevating conveyer, and an extensible side wall connection between said conveyers to confine the material to the path of said discharge conveyer when said conveyers are disposed in various angular relationships with respect to each other including a plate extending along the sides and across the forward end of said discharge conveyer, a pair of curved side walls having slidable engagement with the upper side of said plate, each of said side walls having pivotal connection with its respective side of said elevating conveyer, another pair of curved side walls, each of said latter side walls being mounted for extensible movement with respect to said first mentioned side walls, a pair of rectilinear guides formed in said plate and extending along opposite sides of said discharge conveyer, a pair of plates spaced above said first mentioned plate, each of said plates having a guide aligned with said respective guide in said lower plate in the underside thereof, means on said last mentioned side walls having slidable engagement with said guides, and means to prevent the accumulation of material in said lower guides comprising a pair of closure members, said closure members being pivotally mounted adjacent opposite sides of said discharge conveyer for yieldable engagement with said side walls and having a portion resting on said plate and covering said lower guides.

8. In a low vein loading machine, a track mounted truck, an elevating conveyer mounted on said truck for swinging movement with respect thereto about a vertical axis and including an inclined elevating portion mounted for vertical adjustment about a horizontal transverse axis disposed above and adjacent the forward end of said truck and a horizontal discharge portion fixed against vertical movement with respect to said truck, a discharge conveyer mounted on said truck for pivotal movement about a vertical axis, said discharge conveyer extending rearwardly along said truck from a point disposed forwardly of the discharge end of said elevating conveyer in close vertical relationship with respect to said elevating conveyer, and means to confine the material to the path of said discharge conveyer when said conveyers are disposed in various angular relationships with respect to each other comprising an extensible side wall connection between said conveyers including a plate extending along the upper sides and across the forward end of said discharge conveyer, a pair of side walls having slidable engagement with said plate and having pivotal connection with opposite sides of said elevating conveyer at points disposed adjacent but spaced laterally from the discharge end thereof, another pair of side walls, each of said latter side walls having slidable engagement with one of said first mentioned side walls, said plate having a pair of spaced guides extending along opposite sides of said discharge conveyer, and slidable guiding connections between said last mentioned side walls and said guides.

9. In a low vein loading machine, a track mounted truck, an elevating conveyer mounted on said truck for swinging movement with respect thereto about a vertical axis and including an inclined elevating portion mounted for vertical adjustment about a horizontal transverse axis disposed above and adjacent the forward end of said truck and a horizontal discharge portion fixed against vertical movement with respect to said truck, a discharge conveyer mounted on said truck for pivotal movement about a vertical axis, said discharge conveyer extending rearwardly along said truck from a point disposed forwardly of the discharge end of said elevating conveyer in close vertical relationship with respect to said elevating conveyer, and means to confine the material to the path of said discharge conveyer when said conveyers are disposed in various angular relationships with respect to each other comprising an extensible side wall connection between said conveyers including a plate extending along the upper sides and across the forward end of said discharge conveyer, a pair of side walls having slidable engagement with said plate and having pivotal connection with opposite sides of said elevating conveyer at points disposed adjacent but spaced laterally from the discharge end thereof, another pair of side walls, each of said latter side walls having slidable engagement with one of said first mentioned side walls, a pair of guides formed in said plate and extending along opposite sides of said discharge conveyer, slidable guiding connections between said last mentioned side walls and said guides, and means to prevent the accumulation of material in said guides including closure members having pivotal connection with opposite sides of said discharge conveyer and having yieldable engagement with said side walls.
